Primary Examiner — Elizabeth J Oswecki*Assistant Examiner* — Lacey Chey Bowman(74) *Attorney, Agent, or Firm* — Greenblum & Bernstein, P.L.C.(57) **CLAIM**

The ornamental design for a SURVEILLANCE CAMERA as shown and described.

DESCRIPTION

FIG. 1 is a front, left and top perspective view of a SURVEILLANCE CAMERA, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the SURVEILLANCE CAMERA that form no part of the claimed design.
